UNITED STATES PATENT OFFICE.

HENRY M. LAMBERT, OF PORTLAND, OREGON.

ROTARY ENGINE.

1,271,178.

Specification of Letters Patent.

Patented July 2, 1918.

Application filed October 13, 1916, Serial No. 125,473. Renewed December 26, 1917. Serial No. 208,979.

To all whom it may concern:

Be it known that I, HENRY M. LAMBERT, residing at Portland, in the county of Multnomah and State of Oregon, have invented 5 certain new and useful Improvements in Rotary Engines, of which the following is a specification.

My invention relates to certain new and useful improvements in rotary engines and 10 the invention particularly has for its object to provide an engine which may be used for a number of purposes and while especially designed for use as an internal combustion engine it may be nevertheless, with but 15 slight modification, employed as a steam engine, a rotary pump, a rotary air compressor, or a rotary power blower.

In its generic nature, the invention comprises an annular casing in bearings of 20 which the operating shaft is journaled in a position eccentric to the center of curvature of the casing. The casing is formed with one or more chambers (depending on the use to which the invention is to be put) 25 and on the shaft is an annular rotator, the periphery of which is concentric with the shaft and engages the periphery of the casing at one place only. The rotator is provided with radially movable abutments, the 30 construction of which and the devices employed for the extension of the abutments to maintain the abutment pistons in contact with the peripheral wall of the casing, constitute one of the essential features of my 35 invention and consist of pendulum devices having a wedge-like connection with the abutments, whereby to impart the necessary outward movements to the abutments in a positive manner and with the required differential movement due to the eccentricity 40 of the casing chamber with relation to the shaft casing.

Another object of the invention is to provide a structure especially adapted as an internal combustion engine in which the casing is made with two chambers and two rotators are employed, each rotator being of the same general construction, save that the one rotator on the compressing side is provided with compressed charge transferring 50 ducts, while the rotator on the explosion side is without such ducts; on the compressing side, the casing is provided with an intake port designed to be connected up with 55 the usual carburetor, and on the explosion

side it is also provided with a spark plug aperture to receive the spark plug of the ignition mechanism, while on the explosion side no ducts are provided in the peripheral wall of the casing, excepting the exhaust 60 port which registers with the exhaust duct, and the dividing wall or web of the casing is provided with a cross port, and on one side with a new charge admission cross port and at the other side with a compressed 65 charge outlet duct registering with the cross port and designed to deliver the compressed charge into the explosion side of the casing; the explosion side of the casing may also be water-jacketed for cooling purposes or cooling 70 effected in any other way known in gas engine practice.

The invention also includes those novel features of construction, combination and arrangement of parts, all of which will be 75 first fully described, then be specifically pointed out in the appended claims, and illustrated in the accompanying drawings, in which:—

Figure 1 is a perspective view of my engine constructed as an internal combustion 80 engine.

Fig. 2 is a vertical cross section taken substantially on the line 2—2 of Fig. 4, the rotator and the parts carried thereby being 85 shown in elevation and one of the pendulum cover plates being removed.

Fig. 3 is a cross section on the line 3—3 of Fig. 4 looking in the direction of the arrow, the rotator and its carried parts being shown 90 in elevation, a portion of the rotator being broken away to show the compressed charge transfer duct.

Fig. 4 is a one-half top plan view and a one-half horizontal section of the invention. 95

Fig. 5 is an enlarged detail view showing the sealing packing to prevent gas escape by the rotator at the place where it contacts the 100 annular wall of the casing.

Fig. 6 is a detail perspective view of one of the pistons.

Fig. 7 is a detail perspective view of one of the sliding abutments, one arm of which has been removed.

Fig. 8 is a detail perspective view of the sliding abutment arm that has been removed from the parts shown in Fig. 7.

Fig. 9 is a detail view on a smaller scale showing the cross port in the dividing web. 110

of the casing and showing the new charge inlet groove in the web, the view being taken from the explosion side of the casing.

Fig. 10 is a view similar to Fig. 9 taken 5 from the compressing side showing the elongated groove in the web that registers with the cross port.

Fig. 11 is a detail cross section on the line 11-11 of Fig. 9.

10 Fig. 12 is a detail vertical section and elevation of a modification of the invention showing the same as adapted for use as a steam engine, a rotary pump, a rotary power blower, or a rotary air compressor.

15 Fig. 13 is an enlarged detail perspective view of one of the pendulum devices, showing the threaded adjustment between the pendulum rod and the pendulum disk.

In the drawings, in which like numerals 20 and letters of reference indicate like parts in all of the figures, 1 represents the casing which is provided with a partition wall 2 that separates the casing into two chambers having annular peripheral walls and closed 25 by heads 4 that are secured to the flanges 3 of the casing. The heads 4 of the casing are provided with shaft bearings 5 which are located eccentrically to the center of curvature of the casing peripheral wall and in 30 which the operating shaft 6 is journaled.

Keyed or otherwise secured to the shaft 6 are two rotators 7-7^a, one rotator 7, being located in the working chamber of the casing and the other 7^a being located in the 35 compressing chamber of the casing. As the construction of each rotator is the same (except that the rotator 7^a is provided with a compressed charge transferring duct herein-after referred to) a detailed description of

40 one of the rotators will, it is believed, suffice. The rotator 7 is provided with radial ways 8-9 in which the sliding abutments operate, there being two sliding abutments radially opposed on each rotator 7 and each sliding 45 abutment consists of a head 14 and arms 15 which are secured to the head by countersunk screws 16, or other suitable fastening devices. The arms 15 are slotted as at 17 to pass over the shaft 6 and at their inner 50 ends are provided with circular faces 18 that merge with the adjacent faces of the wedge members 19 to coöperate with the pendulum disks 41 that are carried by the pendulum rods 42 which are fulcrumed at their 55 outer ends on pins 43 and lie in recesses 10 in the rotator. The rotator is countersunk as at 11 so that cover plates 12 may be fastened by screws 13, or otherwise, over the recesses 10 to form a smooth surface of the rotator.

60 Each abutment head 14 is provided with a transverse socket 20 to receive the cylindrical shank 21 of the abutment piston 22 which is rockable in the recess 20 and is designed to engage the peripheral wall of the 65 casing at all times

23 is the exhaust port on the working side of the casing and which registers with the exhaust duct 24.

The casing may be provided with a recess 25 at the place of contact with the rotator in which a packing plate 26 is located, the contacting surface between the plate 26 and the rotator 7 being in engagement throughout the area of the plate 26, except that the entrant corner 26^a may be rounded off to 70 provide easy passage of the pistons 22. A spring 27 may bring the plate 26 in engagement with the rotator and a plug 28 may be provided to permit access to the spring 27.

29 is the spark plug aperture on the working side of the casing to receive the spark plug 30 and that portion of the working side of the casing in which the explosion occurs and in which the greatest heat is generated may be water-jacketed, as at 31, for cooling 80 purposes.

The compression rotator 7^a is provided with a port 37 through which the compressed charge is admitted to the duct 38, the latter duct communicating with the cross 90 outlet 36 that registers with the groove 35 in one face of the partition 2, the groove 35 being a blind groove and communicating only with the cross port 32 that delivers the compressed charge into the groove 33 on the 95 working side of the partition, the groove 33 having a peripheral outlet 34 to deliver the compressed charge into the working chamber where it is exploded at the proper time by the spark at the plug 30.

39 is the new charge inlet port that communicates with the intake duct 40, the latter duct being adapted for connection with the usual carburetor.

When the invention is to be used as a 105 steam engine, blower, pump, etc., only one section of the casing and one rotator is required (see Fig. 12) and in that form 40^a designates the inlet and 24^a the outlet through which the fluid is admitted and let 110 out.

In order to take up wear, the disks 41 of the pendulums may be threaded onto the stems 42 as at 44 (see Fig. 13) and I desire it understood that suitable packing rings 115 may be provided and located wherever found desirable, to prevent undue escape of fluid, and furthermore any suitable lubricating system may be employed in connection with my invention.

It will be observed that by my construction the necessary differential movements of the abutments are allowed for through the action of the pendulum devices and from the foregoing description taken in connection with the accompanying drawings, it is thought the complete construction, operation and advantages of my invention will be readily understood by those skilled in the art.

130

What I claim is:

1. In a rotary engine, an annular casing having shaft bearings, an operating shaft journalized in said bearings and located eccentrically to the center of curvature of said casing; a rotator disk concentrically mounted on said shaft and adapted to engage the peripheral surface of said casing at one place, a pair of sliding abutments radially 10 slidable on and carried by said rotator, abutment pistons journalized in the ends of said abutments to engage the periphery of said casing, and pendulum devices operatively engaging said abutments for separating the same to maintain the pistons in contact with the peripheral wall of the casing and inlet and outlet ports for said casing.
2. In a rotary engine, an annular casing having shaft bearings, an operating shaft journalized in said bearings and located eccentrically to the center of curvature of said casing; a rotator disk concentrically mounted on said shaft and adapted to engage the peripheral surface of said casing at one place, a pair of sliding abutments radially 20 slidable on and carried by said rotator, abutment pistons journalized in the ends of said abutments to engage the periphery of said casing, and pendulum devices operatively engaging said abutments for separating the same to maintain the pistons in contact with the peripheral wall of the casing, said pendulum devices including pendulum members pivoted to said rotator and having abutment engaging disks located between the opposing ends of the abutments and inlet and outlet ports for said casing.
3. In a rotary engine, an annular casing having shaft bearings, an operating shaft journalized in said bearings and located eccentrically to the center of curvature of said casing; a rotator disk concentrically mounted on said shaft and adapted to engage the peripheral surface of said casing at one place, a pair of sliding abutments radially 30 slidable on and carried by said rotator, abutment pistons journalized in the ends of said abutments to engage the periphery of said casing, pendulum devices operatively engaging said abutments for separating the same to maintain the pistons in contact with the peripheral wall of the casing, said pendulum devices comprising pendulum rods pivoted at their outer ends to said rotator and having disk members at their inner or opposing ends to lie between the opposing ends of said abutments, said abutments having opposing ends provided with wedge members co-operative with said pendulum disks for the purposes specified and inlet and outlet ports for said casing.
4. In a rotary engine, a casing having two chambers separated by a partition wall, shaft bearings carried by said casing and arranged eccentrically to the center of cur-
- vature of the casing, a shaft journalized in said bearings, rotators on said shaft, one located in each chamber, each of said rotators including disks concentrically mounted on said shaft and engaging the peripheral wall of said casing at one place, sliding abutments mounted on said rotators and having inner opposing ends, casing engaging pistons journalized in the outer ends of said abutments, pendulum devices mounted on said rotators and projecting between and co-operatively engaging the opposing ends of said abutments to maintain said abutment pistons in contact with the peripheral wall of said casing, said dividing wall having a cross port and a leading groove in one side of the wall communicating with the chamber of the casing on that side and having a blind groove in the other side of the wall, one of said rotators having a compressed charge duct, one end of which opens into said casing and the other end is ported to register with said blind groove at intervals, a new charge inlet port to one of the chambers of said casing and an exhaust duct 40 from the other chamber of said casing, all being arranged whereby a new charge is drawn into one of said casing chambers, compressed in said chamber and transferred to the other chamber, and means for exploding said compressed charge in said other chamber before exhausting the same to atmosphere.
5. In a rotary engine, a casing having two chambers separated by a partition wall 100 shaft bearings carried by said casing and arranged eccentrically to the center of curvature of the casing, a shaft journalized in said bearings, rotators on said shaft, one located in each chamber, each of said rotators including disks concentrically mounted on said shaft and engaging the peripheral wall of said casing at one place, sliding abutments mounted on said rotators and having inner opposing ends, 105 casing engaging pistons journalized in the outer ends of said abutments, pendulum devices mounted on said rotators and projecting between and co-operatively engaging the opposing ends of said abutments to maintain said abutment pistons in contact with the peripheral wall of said casing, means for admitting new charges into one of the chambers of said casing at one side of the place of contact between the casing 110 and the rotator to be compressed on the other side of said place of contact, means for transferring the compressed charge from one chamber of the casing into the other chamber, means for exploding the 115 compressed charge in said other chamber, and an exhaust port to said other chamber through which said exploded charge is exhausted to atmosphere.
6. In a rotary engine, a casing having 120

- two chambers separated by a partition wall, shaft bearings carried by said casing and arranged eccentrically to the center of curvature of the casing, a shaft journaled in said bearings, rotators on said shaft, one located in each chamber, each of said rotators including disks concentrically mounted on said shaft and engaging the peripheral wall of said casing at one place, sliding abutments mounted on said rotators and having inner opposing ends, casing engaging pistons journaled in the outer ends of said abutments, pendulum devices mounted on said rotators and projecting between and co-operatively engaging the opposing ends of said abutments to maintain said abutment pistons in contact with the peripheral wall of said casing, said dividing wall having a cross port and a leading groove in one side of the wall communicating with the chamber of the casing on that side and having a blind groove in the other side 55 of the wall, one of said rotators having a compressed charge duct, one end of which opens into said casing and the other end is ported to register with said blind groove at intervals, a new charge inlet port to one 60 of the chambers of said casing and an exhaust duct from the other chamber of said casing, all being arranged whereby a new charge is drawn into one of said casing chambers, compressed in said chamber, and 65 transferred to the other chamber, means for exploding said compressed charge in said other chamber before exhausting the same to atmosphere, said sliding abutments having their opposing ends separated and provided with web members, said pendulum devices including pendulum arms pivoted at one end and pendulum disks on the other ends of said arms, said disks being located between the opposing 70 web portions of the abutments, substantially 75 as shown and described.
8. In a rotary engine, a piston casing having inlet and outlet ports, a rotator disk, a shaft journaled in said casing on 80 which said disk is carried, a pair of sliding abutments radially slideable on and carried by said rotator to divide the piston chamber into compartments, said casing having inlet and outlet ports, and pendulum devices operatively engaging said abutments for separating the same to maintain the abutments in contact with the peripheral wall of the piston chamber of the casing.

HENRY M. LAMBERT.
